CLAIM

The ornamental design for a combined and compartment tray for packaged seasonings or the like, substantially as shown.

DESCRIPTION

FIG. 1 is a perspective view of a combined tray and compartment for packaged seasonings or the like embodying my new design;

FIG. 2 is a top plan view thereof;

FIG. 3 is a bottom plan view thereof;

FIG. 4 is a side elevational view thereof;

FIG. 5 is a front elevational view thereof, the rear being identical;

FIG. 6 is a sectional view taken in the direction of the arrows on line 6—6 of FIG. 5;

FIG. 7 is a reduced exploded perspective view thereof.

FIG. 1
